US00D452116B1

(12) **United States Design Patent** (10) Patent No.: **US D452,116 S**
McDonough et al. (45) Date of Patent: ** Dec. 18, 2001

(54) **TRAINER CUP**

(76) Inventors: **Justin E. McDonough**, 12 Ballentine St., Kenvil, NJ (US) 07847; **Steve Aridgides**, 327 Michael Rd., Yardley, PA (US) 19067

(**) Term: **14 Years**

(21) Appl. No.: **29/143,057**

(22) Filed: **Jun. 6, 2001**

Related U.S. Application Data

(60) Division of application No. 29/124,904, filed on Jun. 12, 2000, which is a continuation-in-part of application No. 29/116,372, filed on Dec. 30, 1999.

(51) LOC (7) Cl. **07-01**

(52) U.S. Cl. **D7/510; D7/511**
